(57) **CLAIM**

We claim the ornamental design for a plunger for a feminine hygiene product, as shown and described.

DESCRIPTION

FIG. 1 is a front perspective view of the plunger for a feminine hygiene product, showing our new design; FIG. 2 is a rear perspective view thereof; FIG. 3 is a left side elevation view thereof; FIG. 4 is a right side elevation view thereof; FIG. 5 is a front elevation view thereof; FIG. 6 is a rear elevation view thereof; FIG. 7 is a top elevation view thereof; and, FIG. 8 is a bottom elevation view thereof. The broken lines depict portions of the plunger for a feminine hygiene product that form no part of the claimed design.
